UNITED STATES PATENT OFFICE.

FRANK STONE, OF LONDON, ENGLAND.

APPARATUS FOR AUTOMATICALLY PLAYING KEYED INSTRUMENTS.

No. 844,052.

Specification of Letters Patent.

Patented Feb. 12, 1907.

Application filed May 18, 1903. Serial No. 157,667.

To all whom it may concern:

Be it known that I, FRANK STONE, organ-builder, a citizen of the State of Massachusetts, residing at Erskine Road, London, England, have invented certain new and useful Improvements in Apparatus for Automatically Playing Keyed Instruments, of which the following is a specification.

This invention has for its object to improve the construction of apparatus for automatically playing keyed instruments, such as pianofortes, and is illustrated in the accompanying drawings, in which—

Figure 1 is an elevation of this apparatus with as much of a pianoforte shown as is necessary to illustrate the application of this apparatus when in use. Fig. 2 is a sectional elevation showing certain parts of the apparatus, others not forming part of this invention being omitted. Fig. 3 is a plan of this apparatus, partly in section, and of part of a pianoforte, and serves to illustrate certain parts of this invention. Fig. 4 is an elevation of certain parts on an enlarged scale, and Fig. 5 is a plan of Fig. 4. Fig. 6 is an elevation of a portion of the casing and shows the shoe or bracket for the pedals. Fig. 7 is a sectional elevation corresponding with Fig. 6. Fig. 8 is a front elevation, parts being broken away, of the parts shown in Figs. 6 and 7.

In order to permit an apparatus of this kind to be used with pianofortes or the like of varying dimensions, it is necessary to provide means permitting the fingers of the apparatus to strike the keys of the piano, say, exactly as and where the fingers of a skilful performer would touch the same. It is therefore requisite that the fingers may be raised or lowered to a certain extent, that they may be brought nearer to or removed farther from the "fall" of the pianoforte, and that nevertheless the pedals that work the apparatus be so supported that they will not tend to overturn the apparatus, as is the case with some older forms.

Another requirement in an apparatus of this kind is that the music-sheet may pass over the "tracker" in such a manner that the perforations in the sheet come exactly over the openings in the tracker. Moreover, the pneumatic power must be so admitted to the primary bellows that even when the apparatus is set to play softly the action of the primaries shall be certain and prompt. These several requirements are

fulfilled by this invention as follows: The first operation to be effected in applying the apparatus to a pianoforte or the like is so to place and retain it that the fingers be at the right point both laterally and in the direction of the length of the keys. The apparatus is therefore fitted at each end with the arrangement seen in Figs. 1 and 3 and separately shown on an enlarged scale in Figs. 4 and 5. This arrangement is carried by a bracket A, secured in place by screws or the like. In this bracket A works a rod a, threaded so as to screw inward or outward, as required. A lock-nut a' serves to secure it in the proper position. The rod a carries a padded button or head a², which bears against the front of the pianoforte when the apparatus is in position. On the bracket A a slide b is provided, in which moves a dovetailed block b', carrying a bar b², a set-screw b³ serving to secure the block b' in place.

When the apparatus is moved up to the pianoforte, the rods a and bars b² are drawn back, the apparatus is adjusted (by moving it to or fro) until the fingers fall correctly on the keys. Then the rods a are screwed outward until the head a² touches the piano-front and then screwed by the lock-nuts a'. This prevents the apparatus moving forward toward the pianoforte when the pedals are worked. The bars b² are then adjusted by moving the blocks b' until the said bars b² touch the key-blocks of the pianoforte, as illustrated in Fig. 3. The bars are then secured in place with the blocks on which they are mounted by drawing tight the set-screws b³. It will generally be found desirable so to mount the bars b² that when in position against the key-block each will slightly depress the key just under such bar. This adjustment of the bars b² prevents lateral displacement of the apparatus. It will now be necessary to adjust the fingers as to the height—that is to say, the fingers must be brought to such position as to just touch the piano-keys when at rest in readiness to depress the keys when actuated by the corresponding pneumatics. The means adopted for this purpose are shown in Figs. 2 and 3.

B B are the pneumatics actuating the fingers by wires or rods B' B', as usual. C C are the fingers. All fingers C C have their fulcrum in a bar C', extending entirely across the apparatus. As will be seen more particularly in Fig. 3, the ends c of the bar C' are guided

in grooves or recesses in the case of the apparatus and mounted on screw-rods c' , nuts C^2 serving to secure the same to be secured in proper position. This arrangement permits the front or striking end of the fingers to be raised or lowered as required without interfering with the rear ends upon which the wires $B' B'$ act. The apparatus and fingers being thus brought into proper position the 10 pedals have to be so supported as not to exert a pull on the case of the apparatus, as this would tend to sway the whole. The 15 pedals D are therefore mounted in a shoe or bracket D' capable of up-and-down movement. On the casing of the apparatus are provided wing-pieces $D^2 D^2$, which have slots $d' d'$. In the slots $d' d'$ work screw-threaded 20 studs $d d$, fixed on the sides of the shoe or bracket D' . Upon the studs $d d$ run thumb-nuts $d^2 d^2$. When the whole apparatus is to be set up, the thumb-nuts are loosened and the shoe D' allowed to drop until the casters or rollers $d^3 d^3$ thereon securely rest on the floor. The nuts are then tightened again 25 and hold the shoe in place.

When the apparatus is in proper position, the nuts d' are loosened and the shoe D' permitted to drop until the bottom board of the same rests on the floor. The nuts are then 30 tightened again. The parts being so fixed, the pressure of the outer end of the pedals D , taken by the shoe D' , is exerted on the floor. The pressure of the inner ends being exerted upon the bellows, there will thus be no tendency 35 to pull over the case.

The thumb-nuts d^2 form the ends of a rod passing from side to side of the case between the boards that inclose the space wherein the 40 pedals work. The studs project outside the boards forming the recess, the remainder of the rod being within the recess.

In order to insure that the primary pneumatics may act promptly and forcibly even when the apparatus is set to play "piano" or "pianissimo," the chamber or trunk containing such primary pneumatics is, by a pipe E , (see Fig. 2,) connected with the main pressure-chest, so that although the power depressing the fingers is small, as is necessary 45 for playing piano, yet sufficient pressure is exerted at all times upon the primary pneumatics to insure their prompt action.

In order to permit the music-sheet to move over the tracker with absolute exactness, the spool is mounted in a slide or carriage capable of some lateral movement. This is illustrated in Figs. 2 and 3.

F is the carriage, $F' F'$ being two rollers or spools for the music-sheet G . (Not shown in Fig. 3.) The spools and music-sheet are 60 of the usual construction. The carriage F slides to and fro and is guided on two studs ff , fixed in the case and passing through slots in the bottom board of carriage E . The movement of the carriage is effected by a bar 65 or lever g , which at h is hinged to the front of the tracker and at h' embraces a stud or pin on carriage F , so that by the bar g the carriage is moved.

I claim—

1. In apparatus for automatically playing keyed instruments an arrangement at each end of the apparatus, each such arrangement having a rod adjustable inward and outward by a screw-thread thereon and combined 75 with a lock-nut to secure the same in position, a head on each rod, adapted to bear against the front of the keyed instrument and padding on such head the whole rod and head arrangement on each side combined 80 with a slide, a dovetailed block moving in such slide a bar on said block and a set-screw to hold the block in position.

2. In apparatus for playing keyed musical instruments pedals, a shoe or bracket hinged to lower ends of the pedals and capable of adjustment, screw-threaded studs on the brackets wing-pieces on the instrument, having slots for the said studs, and thumb-nuts on the said studs.

3. In apparatus for playing keyed instruments the combination of adjustable stops limiting the forward movement of the whole, adjustable stops limiting the sidewise movement, and means for raising or lowering the 95 fulera of the fingers all provided with set-screws fixing the same in relative position.

In testimony whereof I have hereunto set my hand in the presence of two witnesses.

FRANK STONE.
